No. 739,981.

PATENTED SEPT. 29, 1903.

W. P. BRYANT.
RAILWAY CONSTRUCTION.
APPLICATION FILED MAY 12, 1903.

NO MODEL.

THE NORRIS PETERS CO., PHOTO-LITHO., WASHINGTON, D. C.

UNITED STATES PATENT OFFICE.

WILLIAM P. BRYANT, OF CORONA, CALIFORNIA, ASSIGNOR OF SEVEN-EIGHTHS TO W. B. ROBERTS, G. W. GRAY, D. W. WALKINSHAW, P. S. GRUENDIKE, W. N. TILSON, H. A. WOOD, AND W. G. TOWER, OF CORONA, CALIFORNIA.

RAILWAY CONSTRUCTION.

SPECIFICATION forming part of Letters Patent No. 739,981, dated September 29, 1903.

Application filed May 12, 1903. Serial No. 156,819. (No model.)

To all whom it may concern:

Be it known that I, WILLIAM P. BRYANT, a citizen of the United States, residing at Corona, in the county of Riverside and State of California, have invented a new and useful Railway Construction, of which the following is a specification.

This invention relates to the road-beds of railways, more particularly to the construction of the rails and ties and the means for supporting and connecting them, and has for its object to improve and strengthen these parts and to produce a form of rail and supporting means which will better resist the strains to which such structures are subjected and which will increase the durability without material increase of expense.

The invention consists in certain novel features of construction, as hereinafter shown and described, and specified in the claims.

In the drawings, in which corresponding parts are denoted by like designating characters, Figure 1 is a vertical longitudinal sectional elevation. Fig. 2 is a horizontal longitudinal sectional elevation on the line 2 of Fig. 1. Fig. 3 is a transverse section, enlarged. Fig. 4 is a plan view, enlarged, of a section of the tie structure, together with the improved tie-plates applied. Fig. 5 is a detached perspective view of one of the improved tie-plates, enlarged.

The rails are formed in two sections divided longitudinally and with the sections overlapping or "breaking joints," so that no complete transverse joints occur at the rail ends, whereby a much stronger structure is produced.

One of the rail-sections is formed with the usual form of "head" or tread 10 with the vertical web 11 at one side of the center and with one side of the tie-flange omitted, the remaining portion of the tie-flange, as indicated at 12, extending at the side of the least overhang of the head portion 10, as shown in

Fig. 3. The other rail-section is formed with a vertical web-section 13 of less thickness

than the web-section 11 and with the remainder of the tie-flange 14 extending therefrom, as shown.

The rail members containing the thicker web-sections 11 will be placed at the outside of the roadway, while the thinner members will be at the inner sides, as shown.

The combined web-sections 11 13 will come centrally beneath the head 10, so that the overhang of the head is substantially the same at both sides, as shown in Fig. 3. The outer sections 10 11 12 are placed end to end and the sections 13 14 are likewise placed end to end, but with their abutting ends opposite the centers of the other sections, so that they "break joints" throughout the length of the line.

At the ends and centrally of the vertical webs of each section transverse apertures are formed which "register" when the rail-sections are placed in position and provide means for the reception of clamp-bolts 15 and nuts 16, the joints being further strengthened by clamp or "fish" plates 17, as shown. By this arrangement the web-section 13 forms a strong support to the greater "overhang" of the head portion 10, and when the two parts are clamped together by the bolts and clamp-plates a continuous rail is produced which is very strong and rigid and practically jointless.

When railway-rails constructed in the ordinary manner are to be united with the improved construction of rail, a portion of the tie-flange section 14 will be removed, leaving a short portion of the web-section 13 remaining to form a clamp-plate, as at 18, to be connected to the vertical web 19 of the abutting rail end, as shown at the right of Figs. 1 and 2. By this simple means a joint fully as rigid as any ordinary rail-joint will be produced, so that no perceptible break or jar will be noticeable in passing from the old construction to the new, or vice versa.

The rails are mounted upon transverse ties 20 of the usual construction except that they

are placed at greater distances apart and connected beneath the rail outer sections 10 11 12 by longitudinal tie-sections 21, as shown.

Between the rails and the transverse ties 20 5 are placed metal tie-plates 22, the plates extending inwardly for a considerable distance and with their outer ends turned backwardly over the outer portions of the rail-flange sections 12, as at 28.

10 The tie-plates are formed with lateral extensions 23, projecting over the upper surfaces of the adjacent longitudinal tie-sections 21 and provided with downwardly-extending wings engaging the sides of the members 21, 15 as shown. The tie-plates, including the wings, will be secured in place, as by spikes or bolts 25, as shown. By this simple means a very strong continuous tie-support is formed for the rails, whereby the rails are 20 firmly supported throughout their entire lengths, leaving no "gaps" into which the rails can be depressed by the weight of the passing trains. The road-bed is thus uniformly supported throughout and permits a 25 very smooth uniform movement of the trains without jar or concussion and is not affected thereby. Rails thus formed and supported will not "creep" or become displaced no matter how severe the jarring or concussion 30 may be, and will be firmly held likewise from spreading or breaking under severe lateral strains. The rails being firmly supported throughout their whole length will not be liable to break or bend under pressure and 35 will not be easily affected by washouts, as water will have little or no effect upon a road-bed thus constructed. A road-bed thus constructed will not "swell" in front of heavy trains, as frequently happens with ordinarily-constructed road-beds, and will therefore permit very much more rapid movement of trains without danger of derailment.

40 The coaction of the tie-plates, with their upturned portions over the rail-flanges and the 45 wings depending below the upper surfaces of the longitudinal tie-sections, is a very important feature of the invention, as the connection between the parts is thereby very materially strengthened and a strong resistance against the "spreading" of the rails provided.

50 The longitudinal tie-sections 21 will be provided with spaced transverse channels 26 in their upper surfaces to provide for drainage when required. The expansion and contraction are so evenly distributed over the whole length of each rail that no perceptible change takes place and no open joints are formed thereby.

55 60 The longitudinal tie-sections 21 will be provided with clips 27 to provide means for the connection of lifting-bars when the road-bed is to be lifted when "ballasting" or "tamping" to "justify" the line. This is also an 65 important feature and obviates the necessity

of disfiguring the tie-sections by crowding lifting-bars beneath them. A road-bed thus constructed can be installed in much less time than those of ordinary construction, and will be very much more durable, smoother running, and less liable to displacement and disalignment. The longitudinal tie-sections also effectually prevent washouts by serving as dams to prevent the ballast from being carried away by water flowing over the tracks. 75

70 A road-bed constructed as above described requires fewer spikes to secure it to the ties, it is much easier to replace, and there is less wear on the rails, as the strains are more uniformly distributed. 80

85 The tie-plates formed as shown and described also possess many advantages, as they distribute the strains over a larger area of the ties, will wear uniformly, will prevent the longitudinal sections from splitting by 90 embracing their opposite sides by the wings 23, and coact with the continuous rail-sections to produce a compact and continuous complete structure, admirably adapted for the purposes described. 90

Having thus described the invention, what I claim is—

1. In railway construction, spaced transverse ties supporting the spaced rails, longitudinal tie-sections beneath said rails and between said transverse ties, and tie-plates between said rails and transverse ties and extended over the adjacent portions of said longitudinal tie-sections and secured thereto, substantially as specified. 100

2. In railway construction, spaced transverse ties supporting the spaced rails, longitudinal tie-sections beneath said rails and between said transverse ties, and tie-plates between said rails and transverse ties and extended over the adjacent portions of said longitudinal tie-sections, and with depending wings engaging the sides of said longitudinal tie-sections, means for securing said rails to said ties and tie-plates, and means for securing said wings to said longitudinal tie-sections, substantially as specified. 110

3. In railway construction, spaced transverse ties supporting the spaced rails, longitudinal tie-sections beneath said rails and between said transverse ties, tie-plates between said rails and transverse ties and extended over the adjacent portions of said longitudinal tie-sections and with the outer ends turned over the base-flange of the rail, 120 and means for securing said tie-plates to the ties and tie-sections, substantially as specified.

4. In railway construction, spaced transverse ties supporting the spaced rails, longitudinal tie-sections beneath said rails and between said transverse ties, and tie-plates between said rails and transverse ties and extended over the adjacent portions of said longitudinal tie-sections, and with depending 125 130

wings engaging the sides of said longitudinal tie-sections and with the outer ends turned over the base-flanges, and means for securing said tie-plates to the ties and tie-sections, substantially as specified.

5. In railway construction, spaced transverse ties supporting the spaced rails, longitudinal tie-sections beneath said rails and between said transverse ties, securing means between said rails and ties and tie-sections, and lifting-clips connected to said tie-sections, substantially as specified.
10. In railway construction, spaced transverse ties supporting the spaced rails, longi-

tudinal tie-sections beneath said rails and between said transverse ties, securing means between said rails and ties and tie-sections, and transverse drainage-channels between said longitudinal tie-sections and the rails, substantially as specified.

20. In testimony that I claim the foregoing as my own I have hereto affixed my signature in the presence of two witnesses.

WILLIAM P. BRYANT.
